UNITED STATES PATENT OFFICE

VERNON LEE MEECE, OF HAMILTON, OHIO

DRAFT-REGULATING AND GRATE-SHAKING DEVICE FOR FURNACES

Application filed August 27, 1928. Serial No. 302,305.

This invention relates generally to improvements in domestic furnaces and has more particular reference to means whereby to regulate the draft and to cause the actuation of the furnace grate, the means being provided operating automatically to open the draft and to shake the grate at a predetermined time especially in the morning so that the building in which the furnace 10 is located will be heated to the proper temperature and this without requiring the services of an attendant in opening the draft door and in shaking the grate.

An important object of this invention 15 sides in the provision of means of this character which may be associated with practically all types of domestic furnaces and this without requiring unusual expenditure for installation.

With the foregoing and other objects in view as the nature of the invention will be better understood, the same comprises the novel form, combination and arrangement of parts hereinafter more fully described, 25 shown in the accompanying drawings and claimed.

In the drawing wherein like reference characters indicate corresponding parts throughout the several views:

Figure 1 is a front elevation of a generally conventional domestic furnace with which is associated my improved mechanism, said mechanism being partially illustrated in cross section,

Figure 2 is a side elevation of the furnace adjacent the mechanism associated therewith, the grate actuating lever being illustrated in cross section,

Figure 3 is a somewhat enlarged vertical section taken substantially upon the line 3-3 of Figure 1 disclosing the power mechanism for actuating the furnace grate,

Figure 4 is a section taken through the back side of the time mechanism of the device, said mechanism being in "off" position,

Figure 5 is a vertical section through this time mechanism casing adjacent one side wall thereof disclosing the mechanism in side elevation,

Figure 6 is a view similar to Figure 4, the mechanism being illustrated in "on" position,

Figure 7 is a perspective of the rheostat switch arm operable to "on" position through the time mechanism to complete the circuit to the electric motor of the grate shaking mechanism,

Figure 8 is a fragmentary perspective of the upper end of the arm actuating time controlled lever,

Figure 9 is an enlarged fragmentary section taken upon the line 9-9 of Figure 4 disclosing the means preferred in attaching the said lever to the winding shaft of an ordinary alarm clock alarm mechanism, and

Figure 10 is a diagrammatic view of the electrical circuit employed in the present invention.

Now having particular reference to the furnace A designates generally a conventional coal burning furnace that includes among other structural features a clean out door B within which is arranged a pivotal draft door C.

This furnace includes the usual fire grate operable by the usual shaft D projecting through the furnace casing directly above the clean out door B and to which in the present instance there is associated an upwardly extending link member 5.

Arranged at the side of the furnace A is a suitable motor housing 6 within which is located a suitable electrical motor 7 one end of the armature shaft of which is journaled within a vertical standard 8, this end of said armature shaft being equipped with a small spur gear 9.

At the rear end of the motor 7 is a standard 10 somewhat similar to standard 8 while journaled horizontally within the upper ends of these standards is a shaft 11, the forward end of which is equipped with a large spur gear 12 that is meshed with said armature shaft gear 9, in Figure 3.

Pivoted to this spur gear 12 is a link member 13, the free end of which is pivoted to a horizontal member 14 slideable through a suitable bearing 15 within the said motor housing 6, the outer end of this member extending

through a slot in the side wall of the housing adjacent the furnace A.

The outer end of this member 14 is pivotally associated with a lever 15 which is in turn pivoted to the upper end of the member 5 associated with the grate shaft D, the obvious result being that when said motor 7 is operating the brake shaft associated member 5 will be rocked to cause the shaking of the grate.

Arranged upon the front side of the casing of the furnace A adjacent the upper end thereof is a cable pulley 16 over which is trained a cable 17 the lower end thereof being suitably associated with the draft door C of the furnace clean out door B.

Arranged upon the motor housing 6 is a time controlled mechanism housing 18 within which is located a generally conventional alarm clock 19. After the alarm spring of this clock has been wound the lower end of a lever 20 is attached to the winding key of the alarm shaft preferably in the manner as illustrated in Figure 9.

The upper end of this lever is formed with a right angular tongue 21 spaced beneath which is a similar tongue 22. The upper tongue 21 is formed with a square opening 23 while the lower tongue 22 is formed in register therewith with a circular opening 24. Slidable through the openings in these tongues is a latch bolt 25 normally urged upwardly by reason of a coil spring 26 surrounding the bolt between said tongues 21 and 22, see Figures 4 and 5.

The upper end of the draft door attached cable 17 is secured to said lever 20 at a point intermediate its ends, this cable extending through a slot in the adjacent side wall of the housing 18 and is guided over a pulley 27 located within the housing directly in back of said slot, see Figure 4.

Located within the housing 18 directly above the alarm clock 19 is a housing 28 within which is located a storage battery 29 disclosed in the wiring diagram in Figure 10. In circuit with this battery 29 is a conventional starting rheostat 30 the contacts of which are arranged upon the outer wall of the housing 28 directly above the alarm clock 19 as in Figure 4.

Complemental to this rheostat 30 is a switch arm 31 normally maintained in "off" position by a coil spring 35 as illustrated in Figure 5. This mechanism is of generally conventional design and detail description thereof is believed unnecessary.

The upper end of this switch arm 31 is formed with an outwardly extending right angular tongue 32 adapted to be engaged by the upper end of the latch bolt 25 of said lever 20 when this lever is swung from the "off" position in Figure 4 to the "on" position in Figure 6, this motion being accomplished by the operation of the alarm mechanism of the clock 19 when the same is released at a

predetermined time. Said rheostat 30 and battery 29 are in circuit with the grate actuating mechanism motor 7 and obviously when the lever 20 is swung in a direction toward the right said switch lever 31 will wipe over the contacts of the rheostat to cause the gradual flow of the current from the battery.

Located at the one end of the rheostat 30 and in circuit with the rheostat the battery and motor is an electro-magnet 33, the purpose of the same being to maintain the switch lever 31 in "on" position. In circuit with the rheostat battery and motor and located beneath the magnet 33 on the outer wall of the casing 28 is a normally closed switch 34 and when the switch arm 31 has reached its limit of movement the lever latch bolt 25 will continue to move and eventually encounter said switch 34 breaking the circuit to the magnet 33 whereupon the switch lever 31 will return to its normal "off" position as in Figure 4.

In this connection it is to be noted that the lever latch bolt is bevelled on its free extremity as at 36, so that the bevelled extremity engages the tongue 32 of the switch arm 31, so that obviously when the said switch arm 31 has reached its limit of movement, the lever latch bolt 25 continually is actuated upon by the winding key of the alarm shaft, the said latch bolt will disengage itself by reason of its bevelled end from the tongue 32 of the switch arm and continue its movement toward the said switch to brake the circuit to the magnet 33 as hereinbefore described.

The housing 18 is provided with a swinging door 18' so that the mechanism may be reset by reaching into the housing and returning the lever 20 to its normal position as in Figure 4 whereupon the draft door C will be closed.

In view of the foregoing description when considered in conjunction with the accompanying drawings the construction and operation of this device will be entirely clear to those skilled in the art.

Even though I have herein shown and described the invention as consisting of certain detail structure features, it is nevertheless to be understood that some changes may be made therein without affecting the spirit and scope of the appended claim.

Having thus described my invention, what I claim as new is:

In a draft regulating and grate shaking device for furnaces wherein the furnace includes a grate shaking shaft together with a draft door, an electrical motor arranged adjacent the furnace and operatively associated with the grate shaft to cause the rocking of the shaft during the operation of the motor, time controlled means operatively associated with the draft door whereby to open the same at a predetermined time and nor-

5 mally open switch unit in circuit with the
motor and a source of electrical supply and
means associated with the time controlled
mechanism whereby to cause the closing of
the switch upon the operation of the door
10 opening mechanism, and magnetically con-
trolled means for maintaining said switch
closed when thrown to "on" position, and a
normally closed switch within the circuit and
located in the path of movement of the time
15 controlled means whereby to break the cir-
cuit to the magnet after the time controlled
mechanism has completed its movement.

In testimony whereof I affix my signature.

15 VERNON LEE MEECE.
